LAMB-COAT

Charles M. Allen, Miles City, Mont.

Application December 18, 1936, Serial No. 116,546

1 Claim. (Cl. 54—79)

My invention relates to certain new and useful improvements in animal blankets or protective means and designed particularly for use on very young lambs. This device may therefore most 5 aptly be called a lamb-coat. During a certain time in the life of a lamb it is very susceptible to changes in weather and many lambs for this reason have been lost and it is a primary object of my invention to provide a lamb-coat of simple, 10 inexpensive construction and adapted to save the lives of lambs under above described conditions. This coat is easily put on and taken off for repeated use.

In the accompanying drawing:

15 Fig. 1 is a plan view of the interior of my improved lamb-coat and Fig. 2 is a modification of Fig. 1 showing an elastic neck band and a portion of the lining broken out to reveal the double thickness of material.

20 Fig. 3 is a further modification of Figs. 1 and 2, illustrating an embodiment of my invention in which the neck band is eliminated.

Fig. 4 is a side view of the coat as it appears on a lamb.

25 Fig. 5 is a perspective view of the type of lamb-coat shown in Fig. 2, on a lamb.

Fig. 6 is a front view of the type of lamb-coat shown in Fig. 3 in position, the lamb being shown in broken lines only.

30 Referring to the drawing by reference letters, like characters designating corresponding parts in the various views: my lamb-coat comprises an approximately quadrangular laminated blanket, preferably two thicknesses of material of which 35 the outer material A is preferably 10-ounce canvas or other suitable weather resisting material and B is a lining of preferably 25% wool.

Both thicknesses are suitably stitched together at the edges preferably being hemmed and 40 stitched as A2 and further stitching as A3 may be made (see Figs. 1, 2 and 3).

In the type of blanket shown in Figs. 1 and 2 the front corner parts are cut on a bias to the front or neck part of the coat which latter part 45 in Fig. 1 comprises a transverse re-enforcing strip B at the respective ends of which is secured a metal ring C and a snap-hook D each retained in an extension strap E fixed on strip B said strips B and E comprising a collar. In the modified 50 form, Fig. 2 the blanket is gathered or puckered forward and centrally to form a half collar F the said collar being completed by connecting its ends with an elastic neck piece F2. When this type of coat is put on a lamb the collar is first slipped 5 over the head of the lamb, the elastic part F2

being underneath at the throat of the lamb (see Figs. 2 and 5).

In all types of my coat it is provided at each of its four outer corners with an elastic loop L, the blanket being of such size that when in place on the back and sides of a lamb the said corners and loops are each in proximity to a leg of the lamb, all four legs being inserted through their adjacent loop. Thus the coat is actually a blanket covering the back, sides and neck of the lamb and is drawn and retained snugly in this protective position, protecting the lamb in severe weather conditions by retaining body heat and eliminating weather penetration and possibility of freezing moisture coming into contact with the 15 body.

It will be readily understood that my lamb-coat provides for ample freedom of the limbs and head, provides warmth and keeps the lamb dry during inclement weather and protects the vital organs, 20 all absolutely necessary to preserve the lives of lambs. This coat is of extremely simple and inexpensive construction and can be used repeatedly according to weather conditions.

In a desired modified form of the device as 25 shown in Figs. 3 and 6, the coat itself is slightly longer, its front corners being extended to form tabs or lapels G intermediate which the front end of the coat is arched or cut back inwardly, centrally as H (Fig. 3). The hemmed edges of this 30 cut back comprises the collar. In putting this type of coat on, the hind legs of the lamb are first inserted in their respective loops of the coat, then the lapels G at the front are crossed under the throat of the lamb and the left leg of the lamb 35 is inserted in the right loop L and vice-versa (see Fig. 6). Thus the coat is actually double breasted, as clearly shown, and at the point where the hemmed edges of the cut back cross there may be provided a friction snap S, or any other suitable 40 fastener where these crossed parts can be connected.

My invention has now been fully disclosed. It will be readily understood that the materials of which it is made may be varied considerably, the 45 main objective in choosing such materials being to have the exterior of good quality moisture shedding and non-wind-penetrating goods, but the lining being of heat retaining quality preferably part wool.

The leg engaging loops L are preferably stitched on at the respective corners, each a complete loop, as in Fig. 1, but they may also be half-loops as in Fig. 2. The neck band or collar may also be varied in construction, for example an ordinary 55

strap and buckle, to replace the ring and snap construction shown in Fig. 1. However an objective of my lamb-coat is to maintain extreme simplicity with maximum efficiency.

5 The size of these lamb-coats is a matter of choice. They are designed primarily for very young lambs and the size may be practically standardized.

In any case, it must be borne in mind, that 10 the size is such that the coat fits snugly over the back and against the sides of a lamb, and with the bands L of proper elasticity there will be no undue strain on the parts affected.

Because of the extreme simplicity and inexpensive construction of my lamb-coat it is obvious 15 that this device is practical and a necessity for sheep owners.

I claim:

A lamb-coat comprising an outer water-proof covering and an inner lining of heat retaining material, said coat comprising further a substantially quadrangular blanket arranged to lie on and cover the back and sides of an animal, an adjustable neck band integral of the front central part of the blanket, an elastic leg engaging loop at each corner of the blanket, the parallel opposite edges of the blanket of a length corresponding to the distance between the front and hind legs 10 of a lamb, the blanket extended thence forwardly in tapered form to the neck band, said band comprising an expansible collar the upper part there-of of non-elastic and comprising the reinforced transverse front end part of the blanket, the 15 remainder of the band being of elastic material.

CHARLES M. ALLEN.
